US00D448315B1

(12) **United States Design Patent** (10) Patent No.: **US D448,315 S**
Ito (45) Date of Patent: ** Sep. 25, 2001

(54) **PORTRABLE OPTICAL DISTANCE
MEASURING DEVICE**

(75) Inventor: **Hideki Ito**, Yokohama (JP)

(73) Assignee: **Nikon Corporation**, Tokyo (JP)

(**) Term: **14 Years**

(21) Appl. No.: **29/133,456**

(22) Filed: **Dec. 1, 2000**

(30) **Foreign Application Priority Data**

Sep. 14, 2000 (JP) 12-025841

(51) LOC (7) Cl. **10-04**

(52) U.S. Cl. **D10/70**

(57) **CLAIM**

The ornamental design for portable optical distance measuring device, as shown.

DESCRIPTION

FIG. 1 is a front perspective view of portable optical distance measuring devices showing my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.
